UNITED STATES PATENT OFFICE.

WALDO P. SCHIRMER, OF LAKewood, OHIO.

ROTARY PUMP.

Application filed January 19, 1925. Serial No. 3,357.

To all whom it may concern:

Be it known that I, WALDO P. SCHIRMER, a citizen of the United States, residing at Lakewood, in the county of Cuyahoga and 5 State of Ohio, have invented certain new and useful Improvements in Rotary Pumps, of which the following is a specification.

This invention relates to improvements in rotary pumps.

10 The primary object is to provide a rotary pump whose capacity is unusually large and one wherein the structure permits of high speed operation without affecting the functioning of the pump elements.

15 Another object is to provide a rotary pump wherein the flow of fluid will be absolutely constant.

20 A further object is to construct a rotary pump including a floating rotor having oppositely directed sets of relatively staggered or alined teeth, the spaces between the teeth opening through the ends of the rotor.

25 A still further object is to provide a pump in which a toothed rotor is driven from an internal gear wheel and is mounted floatably on a spacing disk and supporting means carried by end closures.

30 Other objects will be in part obvious and in part pointed out hereinafter.

In order that the invention and its mode of operation may be readily understood by those skilled in the art, I have in the accompanying illustrative drawings and detailed description thereof pointed out the preferred and one modified embodiment of the same.

35 Figure 1 is a side elevation of the complete pump;

40 Figure 2 is a sectional view taken substantially on the line 2—2 of Figure 1;

Figure 3 is a side elevation of the elements separated, the pump housing being left out;

45 Figure 4 is a view similar to Figure 3, portions in this instance being in section;

Figure 5 is an inner face view of an end closure;

50 Figure 6 is an elevation of a modified form of rotor, the inlet or outlet openings being shown; and

Figure 7 is a face view of the spacing disk.

Heretofore in rotary pumps of the 55 character forming the subject matter of

this application the structure has been such as to prevent use of a multi-vaned rotor for effectively and constantly forcing a fluid through a pipe system. With the structure illustrated in the accompanying drawings and set out in the following specification wherein similar characters of reference designate similar parts, the above faults are eliminated and I provide a rotary pump having a maximum capacity 65 and one which may be operated at a high speed without experiencing the results common to the ordinary pump of this nature.

This pump comprises a pair of spaced head plates or closures 10 which may be 70 of any desired configuration and are adapted for rigid connection to a pump housing or casing 11 as shown in Figure 2, connection being effected by means of bolts or the like 12. While other designs 75 of casings may be employed I, as shown in Figure 2, prefer the type wherein the inlet and exhaust ports or openings 13 and 14 respectively are horizontally alined.

The head plates or closures 10 are provided with openings in their faces and with heads 15 designed to snugly fit within the circular casing 11 and to have the inner faces abut the rotatable elements which will be set forth hereinafter. A drive shaft 80 17 is mounted in the shaft openings. As shown in Figures 4 and 5 these shaft openings 16 are eccentrically arranged in the plates 10 for reasons which will be apparent. Enlarged portions or bosses 85 18 are carried by the head plates to provide a sufficient bearing surface for the shaft 17. Formed upon the upper half of the heads 15 is a pair of alineable crescent shaped portions or supports 19 as shown 90 in Figures 2, 3, and 5. These crescent shaped portions 19 may be integrally cast with the heads 15 as shown, or they may be in the form of extensions on a spacing disk 20 with which they normally contact 95 when the parts are assembled. Each head 15 has a portion of its periphery cut away as shown in Figures 3 and 4 whereby to form ways or recesses 21 such as will permit of unusually efficient operation of the 100 pump as will be apparent from the following description.

Fixed to the shaft and spaced apart by means of the spacing disk 20 is a pair of gear wheels 22 whose teeth fit into the spaces 110

23 between the vanes 24 of a floating rotor 25. This rotor 25 as shown in Figures 3 and 4 comprises a central ring portion or collar 26 having oppositely directed vanes 5 which may be either horizontally aligned or arranged in staggered relation as shown in Figure 3. Arranging the vanes in staggered relation assures constant or even flow of fluid in a pipe system and permits accommodation of a greater volume than in the ordinary pump. This rotor 25 as shown, is supported upon the spacing disk 20 and to a greater or lesser degree upon the crescent shaped portions 19. In a sense this rotor 15 floats upon these supporting elements.

As previously stated the spacing disk 20 may have the crescent portions integrally formed therewith but in this case I have shown them as being carried by the heads 15, 20 said disk being fixed against relative circumferential shifting through the arrangement of dowel pins 27 which set into the recesses formed in the crescent shaped portions 19.

25 The longitudinally spaced gear wheels 22 have their teeth engageable with portions of the rotor, preferably the lower portion as shown in Figure 2. It is clear that fluid entering the inlet port 13 as shown in Figure 2, will be drawn into the spaces 23 between the vanes 24 and squeezed into the upper portions of the pump casing and then carried around and exhausted through the port 14. Arrangement of the ways or recesses 21 in the heads 15 permits entry of a fluid into the pump between the ends of the vanes 24 as well as between the peripheral portions thereof, with the result that the rotor may be driven at a high speed and 30 still accommodate a large volume of fluid. As previously stated the staggered relation of the vanes 24 also eliminates fluctuation of the fluid flow such as is common in the average rotary pump.

40 45 Heretofore to the best of my knowledge the construction of a satisfactory rotary pump of large capacity has been unsuccessful due to the difficulty in providing means for driving a rotor which would operate properly at any speed. My construction provides for the accommodation of a capacity volume at any speed without the danger of fluid by-passing from one end of the rotor to the other, this being cared for 50 through the arrangement of the spacing disk 20 as shown in Figure 4. This spacing disk serves as a stationary partition which divides the rotor into two compartments, each compartment mounting one of the driving gear wheels which is rotated with the drive shaft 17.

55 60 65 In Figure 6 I show a modified form of rotor wherein the vanes are longitudinally aligned. This figure also discloses the relation between the floating rotor and the

ways or recesses 21 which permit fluid to enter between the ends of the vanes as well as at the periphery.

While I have not shown the many types of gears applicable it is clear that the helical arrangement of vanes on the rotor would be quite feasible and advantageous.

Obviously there are certain minor changes in the details of construction which may be resorted to and such of these changes as may fall within the scope of the appended claims I consider within the spirit of my invention.

I claim:

1. A rotary pump comprising a casing, a shaft, a pair of spaced gear wheels fixed to the shaft, a spacing disk between the gear wheels, a floating rotor arranged upon said disk and having vanes engageable with said gear wheels, and means for permitting inlet and exhaust of fluid. 80

2. A rotary pump comprising a casing, a shaft, a pair of spaced gear wheels fixed to the shaft, a spacing disk between the gear wheels, a floating rotor arranged upon said disk and having vanes engageable with said gear wheels, and means for permitting inlet and exhaust of fluid at the periphery and ends of the rotor vanes. 90

3. A rotary pump comprising a casing, a shaft, a pair of spaced gear wheels fixed to the shaft, a spacing disk mounted loosely and eccentrically on the shaft, a floating rotor arranged on the disk and having vanes engageable with portions of the gear wheels, and means for permitting inlet and exhaust of fluid. 95

4. A rotary pump comprising a casing, a shaft extending through said casing, a spacing disk eccentrically and loosely arranged on the shaft within the casing, a rotor, sets of oppositely longitudinally directed vanes on said rotor, gear wheels fixed to the shaft within the rotor and driving the same, and means for permitting inlet and exhaust of fluid. 105

5. A rotary pump comprising a casing, a shaft extending through said casing, a spacing disk eccentrically and loosely arranged on the shaft within the casing, a rotor, sets of oppositely longitudinally directed vanes 115 on said rotor, gear wheels fixed to the shaft within the rotor and driving the same, and means for permitting inlet and exhaust of fluid between the ends of the vanes and through the peripheral ways. 120

6. A rotary pump comprising a casing having side and end members, a drive shaft, gear wheels, a spacing disk eccentrically and loosely arranged on the shaft between said gear wheels, a rotor having a central portion mounted on the disk, two sets of oppositely directed vanes on the central portion, said gear wheels being engageable with the vanes to transmit motion to the rotor, and means for permitting inlet and exhaust of fluid. 125 130

7. A rotary pump comprising a casing having side and end members, a drive shaft, gear wheels, a spacing disk eccentrically and loosely arranged on the shaft between said gear wheels, a rotor having a central ring portion mounted on the disk, two sets of oppositely directed relatively staggered vanes on the central portion, said gear wheels being engageable with the vanes to transmit motion to the rotor, and means for permitting inlet and exhaust of fluid.

8. A rotary pump comprising a casing having side and end members, heads formed upon the inner faces of the end members and having inlet and exhaust ports formed radially therein, substantially crescent shaped portions extending inwardly from said heads, a shaft extending through the end members and eccentrically arranged therein, a spacing disk loosely and eccentrically arranged upon said shaft, a pair of driving gear wheels fixed to the shaft at opposite sides of the spacing disk, and a rotor arranged to float on said disk and crescent shaped portions and having vanes engageable with said driving gear wheels.

9. A rotary pump comprising a casing having side and end members, heads formed upon the inner faces of the end members and having inlet and exhaust ports formed radially therein, crescent shaped portions extending inwardly from said heads, a shaft extending through the end members and ec-

centrically arranged therein, a spacing disk loosely and eccentrically arranged upon said shaft, a pair of driving gear wheels fixed to the shaft at opposite sides of the spacing disk, a rotor having a central portion loosely supported on the disk, oppositely directed sets of relatively staggered vanes arranged to float over the crescent shaped portions and to engage the gear wheels whereby to effect rotation of the rotor.

10. In a rotary pump, a rotor comprising a central ring portion, and oppositely directed sets of circumferentially spaced vanes carried by said ring portion.

11. In a rotary pump, a rotor comprising a central ring portion, and sets of oppositely directed relatively staggered vanes extending longitudinally from said ring portion.

12. In a rotary pump, a casing having opposed inlet and exhaust ports, a shaft, a spacing disk eccentrically arranged on the shaft, a gear wheel fixed to the shaft at each side of the disk, a stationary crescent shaped portion connected to each face of the disk, a rotor comprising a ring portion arranged on the disk, and oppositely directed vanes on the ring portion engageable with the gear wheels to transmit motion to the rotor.

In testimony whereof, I affix my signature.

WALDO P. SCHIRMER.
